(57) **CLAIM**

The ornamental design for a watercraft, as shown and described.

DESCRIPTION

FIG. 1 is a front view of the watercraft;

FIG. 2 is a top view of the watercraft;

FIG. 3 is a right side view of the watercraft;

FIG. 4 is a left side view opposite the first side view of the watercraft;

FIG. 5 is a back view of the watercraft;

FIG. 6 is a bottom view of the watercraft;

FIG. 7 is a first perspective view of the watercraft; and,
FIG. 8 is a second perspective view of the watercraft.

The broken lines show portions of the watercraft that form no part of the claimed design.
